US00D525689S

(12) United States Design Patent (10) Patent No.: US D525,689 S
Wozniczka et al. (45) Date of Patent: * Jul. 25, 2006

(54) SINK

(75) Inventors: Peter Wozniczka, Arlington Heights, IL (US); Michael S. Gicela, Northwoods, IL (US)

(73) Assignee: Elkay Manufacturing Company, Oak Brook, IL (US)

() Term: 14 Years

(21) Appl. No.: 29/229,397

(22) Filed: May 6, 2005

(51) LOC (8) Cl. 23-02

(52) U.S. Cl. D23/290

(58) Field of Classification Search D23/270-273, D23/284-286, 292-293.1, 303, 290, 308; 4/662-666, 619, 637-642, 661

See application file for complete search history.

(57) CLAIM

The ornamental design for a sink, as shown and described.

DESCRIPTION

FIG. 1 is a perspective view taken from the top, front and right side of a sink showing our new design;

FIG. 2 is a perspective view taken from the bottom, rear, and left side of the sink shown in FIG. 1;

FIG. 3 is a top plan view of the sink shown in FIG. 1;

FIG. 4 is a bottom view of the sink shown in FIG. 1;

FIG. 5 is a front side view of the sink shown in FIG. 1;

FIG. 6 is a rear side view of the sink shown in FIG. 1;

FIG. 7 is a left side view of the sink shown in FIG. 1; and,

FIG. 8 is a right side view of the sink shown in FIG. 1.
